[57]**CLAIM**

The ornamental design for a floor stand for newspapers,
magazines, and the like, as shown and described.

DESCRIPTION

FIG. 1 is a perspective view of a floor stand for newspapers,
magazines, and the like showing my new design;
FIG. 2 is a rear elevational view thereof;
FIG. 3 is a top plan view thereof;
FIG. 4 is a left side elevational view, the right side being
a mirror image thereof;
FIG. 5 is a bottom plan view thereof; and,
FIG. 6 is a front elevational view thereof.

FIG.1
